UNITED STATES PATENT OFFICE.

KARL BAUMANN, OF URMSTON, ENGLAND, ASSIGNOR TO WESTINGHOUSE ELECTRIC & MANUFACTURING CO., A CORPORATION OF PENNSYLVANIA.

EJECTOR.

Application filed March 16, 1918. Serial No. 222,824.

To all whom it may concern:

Be it known that I, KARL BAUMANN, a citizen of the Confederation of Switzerland, and a resident of Urmston, in the county of 5 Lancaster, England, have made a new and useful Invention in Ejectors, of which the following is a specification.

My invention relates to ejectors and has particular reference to radial-flow ejectors 10 in which the kinetic or velocity energy of a fluid either in gaseous or liquid form is employed to remove fluid either in gaseous or liquid form, or in both of these forms combined, from a region at lower pressure and 15 discharge it into a region at higher pressure.

An object of my invention is to provide a radial flow ejector which shall possess a high degree of uniformity and reliability in performance under varying loads.

Another object of my invention is to produce a radial flow ejector which shall maintain substantially uniform delivery pressures by causing the fluid to be entrained to flow 25 in stream lines which meet tangentially moving streams of entraining fluid at an angle in a manner to produce spiral paths of the mixed fluids through the diffuser of the ejector, the length of the spiral paths 30 varying inversely with the load.

A still further object of my invention is to provide a radial flow ejector in which a greater economy of operation is obtained by imparting to the entrained fluid an increased 35 velocity prior to entrainment in a spirally moving jet of motive fluid.

These and further objects, which will be made apparent throughout the description of my invention, are attained by means of 40 the apparatus described herein and illustrated in the accompanying drawing, in which;

Fig. 1 is a diagrammatic sectional view of a device embodying my invention;

Fig. 2 is a similar view of a modification of the structure illustrated in Fig. 1;

Fig. 3 is a diagrammatic plan view of the device illustrated in Fig. 2;

Fig. 4 is a diagrammatic sectional view 50 of another modification of the construction illustrated in Fig. 1;

Fig. 5 is a similar view of a further modification of my invention;

Fig. 6 is a diagrammatic horizontal view 55 of the apparatus illustrated in Fig. 5;

Figs. 7, 8 and 9 are diagrammatic sectional views of several modifications illustrating some of the ways in which the velocity of the fluid to be entrained may be increased prior to entrainment by the entraining fluid.

It is well known that with ejectors having diffusers of the usual radial type, satisfactory operation is usually only obtained when the ejectors are operating at or about full 60 load, that is to say, when the quantities of fluids passing through them are approximately equal to those for which the ejector has been designed. At partial loads, either the efficiency of such an ejector falls very 65 quickly or the operation of the device becomes unreliable. Owing to the fact that at partial loads the velocities in the diffuser of such an ejector are smaller in proportion to the decreased volume, the pressure to which 70 the fluid can be compressed thereby is considerably reduced.

I propose to employ, in a radial flow ejector, a nozzle construction which is arranged to discharge fluid tangentially into 80 the throat of a radial diffuser, entraining the fluid to be evacuated, the latter fluid being delivered to the throat of the diffuser in such a manner that the stream lines of the entraining and entrained fluids meet at an 85 angle. Since the force of the entraining jets is uniform, the union of the streams of the two fluids produces a component flow of mixed fluids in parallel spiral paths through the diffuser, the character of which are determined by the direction of flow and magnitude of the fluids being entrained. Thus, the spiral paths are shorter at full loads than at light loads, the length of the paths varying inversely with the load. This construction and mode of operation insures a fair degree of uniformity in discharge pressures of the fluids and consequently a high degree of efficiency and reliability in the operation of the ejector.

I further propose to give the fluid to be entrained an initial velocity before it mixes with the motive fluid, since the less the differences in the velocities of the entraining and entrained fluids, where they intermingle 105 in an ejector, the better is the efficiency at which the ejector operates. The velocity of the fluid to be entrained is, therefore made as high as possible in that part of the ejector where it mixes with the entraining 110

fluid. The increase of velocity of the fluid to be entrained may be obtained by a corresponding loss in pressure and, in the case of gaseous fluids, with additional expansion and subsequent increase in the work of compression which has to be effected in the diffuser. To obviate such additional expansion in the throat of the diffuser, I provide means within the inlet passage for accelerating the velocity of the fluid to be entrained, the object of this accelerating means being not to compress the fluid but to prevent further expansion and at the same time cause it to have the highest possible velocity before the fluid meets the entraining fluid issuing from the main operating nozzle of the ejector. Where a fluid to be entrained is a liquid, the increased velocity may be obtained by increasing the height of the liquid column, or by producing an artificial vortex in the fluid entering the ejector. Obviously, both of these means may be employed together.

These and other improvements in the operation of an ejector of the character designated I secure by the apparatus which will now be specifically described with reference to the several figures in the accompanying drawings which show diagrammatically various forms of ejectors constructed in accordance with my invention.

In Fig. 1 a simple form of the improved ejector is shown comprising an inlet 1 for the entraining fluid leading to a ring of tangentially disposed nozzles 2 located at the apex of a conical diffuser 3 which terminates in a collecting chamber 4 having a discharge outlet 5. The fluid to be entrained is admitted through an inlet 6, also located at the apex of the conical diffuser 3 and surrounding the inlet 1 for the entraining fluid. In operation the entraining fluid admitted through the inlet 1 meets the fluid to be entrained entering through the inlet 6 at the exit of the ring of nozzles 2, the mixed fluids then passing through the diffuser 3 in a substantially spiral path. At full load, the path of flow of the mixed fluids is much shorter than at light loads and in an extreme case the ejector may be so designed that at full load the path of flow of the mixed fluids is approximately a straight line from the apex to the base of the diffuser 3.

The conical form of diffuser permits of a very convenient arrangement of the nozzles for the entraining fluid, as said nozzles may be inserted tangentially through the outer wall of the diffuser. As illustrated in Figures 2 and 3, the motive fluid enters through a ring of tangentially disposed nozzles 2 which are arranged to discharge jets into the throat of the conical diffuser 3. The fluid to be entrained passes through the inlet 6 at the apex of the diffuser, and is entrained by jets from the nozzle 2. The

combined fluids are compressed in the diffuser 3 and discharged through the collecting chamber 4. The entraining fluid may be arranged to enter the ejector at a high tangential velocity which will be imparted to the fluid to be entrained, the radial component of the velocity adjusting itself in accordance with the load, as previously described.

In the modification illustrated in Fig. 4, the inlet 6 for the fluid to be entrained is preferably shaped to hyperbolic curves. The nozzles 2 for discharging the entraining fluid into the diffuser 3 are arranged to discharge jets tangentially and in the direction of the diffuser 3. The hyperbolic curved portion of the fluid inlet is situated immediately above the throat of the diffuser so as to give the fluid to be entrained an increased velocity before it is intermingled with the entraining fluid.

I indicate in Figs. 5 and 6 a construction in which the fluid to be entrained is given a spiral movement of increased velocity prior to entrainment in the jets from the main nozzles. As shown, the fluid to be entrained enters a vertically disposed inlet passage 6 which communicates with a central opening in a conical diffuser 3. A ring of nozzles 12 enter the inlet 6 in a radial plane and give to the incoming fluid a rapid whirling motion. The main ejector nozzles 2 are located so as to discharge jets of entraining fluid into the throat of the diffuser 3. The fluids pass in a spiral path through the diffuser 3 and are discharged into a collecting chamber 4 from whence they are exhausted.

In the construction illustrated in Fig. 7 the inlet 6 for the fluid to be entrained is arranged in an axial direction with respect to the diffuser 3, the lower portion thereof being of decreased cross-sectional area to give the incoming fluid an increased velocity. In case the latter fluid is a liquid, a vortex is formed in its outlet from which the liquid is discharged at a considerable increased velocity. The motive fluid enters through the conduit 1 into an annular involute shaped passage 8, and is discharged with a whirling motion through the annular nozzle 7.

I show in Fig. 8 a means for increasing the velocity of the fluid to be entrained which consists in providing suitable helically disposed guides 14 in the inlet passage 6 for the fluid to be entrained and in contracting said inlet passage 6 toward the throat of the ejector. The entraining fluid enters through an involute passage 8 and discharges through an annular nozzle 7 into the throat of the diffuser 3. A collecting chamber 4 communicates with the diffuser 3 and is arranged to discharge the combined fluids in the usual manner. The mixture of the two fluids should preferably take place in

that part of the ejector in which the velocity of the fluid to be entrained is the highest, that is, at the throat of the diffuser, which is the point where the inlet passage 5 should be the smallest. The smaller the size of the throat, the greater is the velocity of the fluid at that point and for this reason the throat should be as small as the maximum load for which the ejector is designed 10 will warrant.

In Figure 9, I show a radial flow ejector in which the inlet passage 6 is annular in form and decreases in cross-sectional flow area toward the throat of the diffuser 3. 15 A ring of accelerating nozzles 15 extend into the annular portion of the inlet 6 for the purpose of delivering jets of motive fluid to increase the rate of flow of the incoming fluid through the inlet 6. As shown, they 20 are directed toward the throat of the ejector so as to give the incoming fluid a spiral motion of considerable pitch. Entraining nozzles 2 discharge jets of entraining fluid tangentially into the throat of the diffuser 25 3 which discharges the mixed fluids into a volute collecting chamber 4.

While I have shown my invention in various forms, it will be obvious to those skilled in the art that it is not so limited, 30 but is susceptible of various other changes and modifications without departing from the spirit thereof, and I desire, therefore, that only such limitations shall be placed thereupon as are imposed by the prior art 35 or as are specifically set forth in the appended claims.

I claim—

1. An ejector comprising an annular conical diffuser having a fluid intake or 40 throat at its apex and a tangentially disposed discharge at its base, a fluid nozzle disposed to discharge motive fluid through the throat into the diffuser in a tangential direction, whereby conical-helical motion is 45 imparted to the entrained fluid in passing through the diffuser, and means for imparting a rotary motion to the fluid to be entrained prior to its entrainment.

2. An ejector comprising an annular conical diffuser having a fluid intake or throat 50 at its apex, an intake passage communicating with said throat, means for discharging entraining fluid into the diffuser in a tangential direction, whereby conical-helical motion is imparted thereto, and means for 55 imparting an accelerating movement to the fluid passing through said intake passage, whereby the difference in the velocities of the entrained and entraining fluids is diminished.

3. An ejector comprising an annular conical diffuser having a throat at its apex and a fluid intake passage communicating with 60 the throat, accelerating nozzles opening into the intake passage for discharging fluid to

increase the velocity of the fluid to be entrained prior to entering the throat of the diffuser, and nozzles for entraining fluid arranged to discharge entraining fluid tangentially into the diffuser. 70

4. An ejector comprising an annular conical diffuser having a throat portion at its apex, a nozzle arranged to discharge entraining fluid into the diffuser in a tangential direction, a substantially axial inlet 75 passage for fluid to be entrained communicating with said diffuser throat, said inlet passage having means for causing the fluid to be entrained to flow into said throat in tangential stream lines, which intersect at 80 an angle the tangential stream lines of the motive fluid, whereby the length of the spiral path of the mixed fluids varies inversely with the quantity of fluid entrained.

5. An ejector comprising an annular conical diffuser having an intake or throat portion at its apex, an inlet passage communicating with said throat portion, means for discharging entraining fluid into the diffuser in a tangential direction, and means in 85 said inlet passage for increasing the velocity of the fluid to be entrained prior to its entrainment.

6. An ejector comprising an annular conical diffuser having a throat portion at its apex, an inlet for fluid to be entrained communicating with said throat portion, means for discharging fluid into the diffuser for imparting a conical-helical motion thereto, and means for accelerating the velocity of 95 the fluid to be entrained prior to entrainment, whereby the velocity differences in the entrained and entraining fluids may be minimized.

7. An ejector comprising an annular conical diffuser having a throat portion at its apex, a nozzle arranged to discharge entraining fluid into the diffuser in a tangential direction, an inlet passage for fluid to be entrained communicating with said throat portion, means for accelerating the velocity of said fluid within said inlet passage, said inlet passage having means for causing the fluid to be entrained to flow into said throat portion in stream lines which intersect at 105 an angle the tangential stream lines of the motive fluid, whereby the length of the conical-helical path of the mixed fluids varies inversely with the quantity of the fluid entrained. 110

8. An ejector comprising an annular conical diffuser having a throat portion at its apex, an inlet passage for fluid to be entrained communicating with said throat portion, a set of nozzles arranged in a radial 125 plane to discharge jets of entraining fluid into said diffuser, and a second set of nozzles arranged in said inlet passage to increase the velocity of the fluid to be entrained prior to entrainment by said first set of nozzles. 130

9. An ejector comprising an annular conical diffuser having a throat portion at its apex, an axially disposed inlet passage for fluid to be entrained communicating with 40
 5 said throat portion, a set of nozzles arranged in a radial plane to discharge jets of entraining fluid tangentially into said diffuser, and a second set of nozzles discharging into said intake passage to increase the 45
 10 velocity of fluid to be entrained prior to entrainment by said first set of nozzles.
10. An ejector comprising an annular conical diffuser communicating at its apex with an inlet passage for fluid to be entrained, 50
 15 and a plurality of sets of nozzles having their discharge openings arranged in separate planes traversing said inlet passage, at least one set of nozzles arranged to discharge motive fluid tangentially into said 55
 20 diffuser.
11. An ejector comprising an annular, diverging diffuser having a substantially central intake or throat, a substantially central inlet for fluid to be entrained communicating 60
 25 with said intake nozzle, means disposed in a radial plane for discharging entraining fluid into said diffuser, and a second nozzle means disposed in a radial plane separated from that of said first nozzle means for increasing the velocity of the fluid to be entrained prior to entrainment by said first 65
 30 nozzle means.
12. An ejector comprising an annular diverging diffuser having an intake or throat portion, an inlet passage communicating with said throat portion, means for discharging entraining fluid into the diffuser in a tangential direction, and means in said 70
 35
- inlet passage for increasing the velocity of the fluid to be entrained prior to its entrainment. 40
13. An ejector comprising an annular diverging diffuser having a throat portion, an inlet for fluid to be entrained communicating with said throat portion, means for discharging fluid into the diffuser for imparting a conical-helical motion thereto, and means for accelerating the velocity of the fluid to be entrained prior to entrainment, 45
 whereby the velocity differences in the entrained and entraining fluids may be minimized. 50
14. An ejector comprising an annular diverging diffuser having a throat portion, a nozzle arranged to discharge entraining fluid into the diffuser in a tangential direction, an inlet passage for fluid to be entrained communicating with said throat portion, means for accelerating the velocity of 55
 60 said fluid within said inlet passage, said inlet passage having means for causing the fluid to be entrained to flow into said throat portion in stream lines which intersect at an angle the tangential stream lines of the motive fluid, whereby the length of the conical-helical path of the mixed fluids varies inversely with the quantity of the fluid entrained. 65

In testimony whereof, I have hereunto subscribed my name this 20th day of February, 1918.

KARL BAUMANN.
